WINDOW

Joseph P. Barbay, St. Louis, Mo.

Application October 13, 1934, Serial No. 748,187

3 Claims. (Cl. 20—50)

My invention relates to sliding window sash construction, and, has for its object to provide a window structure wherein both the upper and lower sash can be raised and lowered in the usual manner, and, also wherein both sash can be swung inwardly so as to render the outer faces of the window panes accessible from within the room for washing, or cleaning the same.

A further object of the invention is to provide sliding sash already in a building with my invention so as to permit the sash being swung inwardly into a room as well as being raised up and down.

A still further object of the invention is the provision of a window sash construction which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1 is an enlarged horizontal sectional view of a window showing both of the sash in full lines as swung into open position and also showing them in their closed position in dotted lines.

Fig. 2 is an inside elevation of a window constructed in accordance with my invention.

Fig. 3 is an inside elevation of a window with a portion thereof broken away and showing the lower sash in its raised position.

Fig. 4 is a view similar to Fig. 2, showing the lower sash disengaged from one of the stile members.

Fig. 5 is a detail showing one of the lower corners of the window frame and the lower sash moved into position ready for being swung inwardly.

Fig. 6 is a detail similar to Fig. 4 showing the lower sash in its swung open position.

Fig. 7 is a side elevation of the right side of the window frame, showing the detachable stile members of the upper and lower sashes in the position they assume when the sashes have been swung into open position.

Fig. 8 is a detail of the detachable stile member of the upper sash.

Fig. 9 is a detail of the detachable stile member of the lower sash.

Fig. 10 is a detail of one of the fixed stile members of the upper sash.

Fig. 11 is a detail of one of the fixed stile members of the lower sash.

Referring to the drawings, the reference character 1 designates a window frame; 2 and 3, the parting beads; 4 and 5, the outside stops, while 6 and 7 designate the inside stops. The reference numerals 8 and 9 designate the balancing weights; 10 and 11, the suspension cords, and 12 10 and 13 the pulleys for the upper window sash frame 14, which may be provided with one or more glasses 15.

Numerals 16 and 17 designate the balancing weights; 18 and 19, the suspension cords and 20 15 and 21 the pulleys for the lower window sash frame 22, which may be provided with one or more glass panes 23. The meeting rails 24 and 25 of the sashes 14 and 22 are beveled in the well known usual manner to form a close joint between 20 them when the upper and lower sash frames are in their closed positions within the window frame 1.

The side member 26 of the upper sash frame 14 is hinged, as at 27, to an independent stile member 28 which is vertically slidable in a way between the parting bead 2 and the outside stop 4 and connected to the suspension cord 12, as clearly shown in Figs. 1 and 2. The opposite side member 26' of the upper sash frame 14 is detachably connected to an independent vertically 30 slidable stile member 29 so that the upper sash frame 14 can be swung inwardly for cleaning the outer face of the window pane 15. The stile member 29 is connected to the suspension cord 13, as 35 shown in Fig. 1.

The hinged stile member 28 is provided upon its inner side face with a groove 30 adapted to receive the tongue 31 of the side member 26 of the sash frame 14 when the sash frame is in its 40 closed position to provide an air tight joint between the side and stile members 26 and 28, respectively. The independent stile member 28 is also provided with a facial groove 32 which is metal lined, as at 33, and is adapted to receive 45 the extended end 34 of a metallic strip 35 secured to the inner side face of the parting bead 2, as shown in Fig. 1. This arrangement prevents the stile member 28 from leaving its way between parting bead 2 and stop 4 when the sash frame 50 14 is moved to an open position. It also acts in the dual capacity of a weather strip.

The side member 26' of the upper sash frame 14 is provided, as shown in Figs. 1 and 10 with a facial groove 37 which extends downwardly a 55

suitable distance from the upper face of the frame and it terminates in a beveled lower face 38. This groove 37 is adapted to receive a tongue 39 having a lower beveled face 40 carried by the 5 inner side face of the stile member 29 when the sash frame is in its closed position.

The side member 26' of the sash frame 14 is also provided with a tongue 41 extending upwardly from the lower face thereof to the lower 10 end of groove 37, and the upper end of the tongue is beveled, as at 42. This tongue 41 is receivable in a facial groove 43 having a beveled upper end in the lower portion of the stile member 29 when the sash frame 14 is in its closed position. This 15 arrangement provides an air tight joint between the side member 26' of the sash frame 14 and the stile member 29 when the sash frame is in its closed position, and also permits of the sash frame being disconnected from the stile member 20 29 through a downward sliding movement of the sash frame 14 relative to the stile member 29.

In order to lock the upper sash frame 14 to the stile member 28 when the sash frame is in its 25 closed position relative thereto, I provide the sash frame with a suitable slidable latch member 44 which is engageable in a facial opening 45 in the stile member 29, which opening is clearly shown in Figs. 7 and 8. A suitable upper sash frame guide plate 46 is carried by the lower outside corner of the stile member 29, as shown in Fig. 1. The stile member 29 is provided with an outer facial groove 47, which may be metal lined, as at 48, to receive the tongue 49 of a metallic strip 50 which is secured to the window frame 35 and also seated in the outside stop 5. This prevents lateral displacement of the stile 29 in its way between the parting bead 3 and the stop 5 and also acts in the dual capacity as a weather strip.

40 The side member 51 of the lower sash frame 22 is hinged, as at 52, to an independent stile member 53 which is vertically slidable in a way between the parting bead 2 and the inside stop 7 and connected to the suspension cord 18, as 45 clearly shown in Fig. 1. The opposite side member 54 of the lower sash frame 22 is detachably connected to an independent vertically slidable stile member 55 so that the lower sash frame 22 can be swung inwardly for cleaning the outside 50 face of the window pane 23. The stile member 55 is connected to the suspension cord 19, as shown in Fig. 1.

55 The hinged stile member 53 is provided upon its inner side face with a groove 56 adapted to receive the tongue 57 of the side member 51 of the lower sash frame 22 when the sash frame is in its closed position to provide an air tight joint between the side and stile members 51 and 53, respectively.

60 The independent stile member 53 also provided upon its outer face with a facial groove 58, which is metal lined, as at 59, and is adapted to receive the extended, or tongue end 60 of the metallic strip 35 secured to the parting bead 2, as shown 65 in Fig. 1. The opposite or inner face of the stile member 53 is also provided with a facial groove 61 which is preferably metal lined, as at 62 and adapted to receive the extended end 63 of a guide plate 64 carried by the inside stop 7, as shown in Figs. 1 and 2. This arrangement prevents the stile member 53 from leaving its way between the parting bead 2 and the inside stop 7 when the lower sash frame 22 is moved or swung into its 70 open position, as shown in full lines in Fig. 1.

The side member 54 of the lower sash frame 22 is provided, as shown in Fig. 1, with a facial groove 66 which extends downwardly a suitable distance from the upper face of the lower sash frame and it terminates in a beveled lower face 5 67. This groove 66 is adapted to receive a tongue 68 having a lower beveled face 69 carried by the inner side face of the stile member 55 when the lower sash frame is in its closed position and moved into its connected position with the stile 10 member 53.

The side member 54 of the lower sash frame is also provided with a tongue 70 extending upwardly from the lower face thereof to the lower end of the facial groove 66. The upper face of 15 the tongue 70 is beveled, as at 71 and is receivable in a facial groove 72 having a beveled upper end formed in the lower portion of the stile member 55 when the lower sash frame 22 is moved into closed position relative to the stile member 55. 20 This arrangement provides an air tight joint between the side member 54 of the sash frame 22 and the stile member 55 when the sash frame is in its closed position relative to the stile member 55. 25

In order to lock the lower sash frame 22 to the stile member 55 when the sash frame is in its 30 closed position relative thereto, I provide the sash frame 22 with a suitable slidable latch member 73, which is engageable in a facial opening 74 in the stile member 55, which opening is clearly 35 shown in Figs. 7 and 9.

The stile member 55 is provided with an outer 40 facial groove 75, which may be metal lined, as at 76, to receive the tongue 77 of a metal strip 78 which is secured to the window frame 1 and partly seated in the parting bead 3. This arrangement prevents displacement of the stile member 55 from its way between the parting bead 3 and the inside stop 8 when the sash frame has been disconnected therefrom and swung into its open 45 position, as shown in full lines in Fig. 1.

The lower sash frame 22 is provided at its upper right hand corner with a guide plate 79, as shown in Figs. 1 and 2.

Suitable block members 80 and 81 are secured 50 to the parting bead strips 2 and 3, respectively, at points opposite the ends of the meeting rails of the upper and lower sashes when the sashes are closed. This prevents air currents from finding their way up between the stile members 28 and 53, and 29 and 55, as will be observed from 55 Figs. 1 and 7.

A suitable hinged stop member 82 is carried by the window frame 1 a suitable distance above the window sill 83 upon which the lower end of the stile member 53 can be seated while the lower sash frame 22 is in an open position. When not in use, the stop member 82 can be swung back so as not to interfere with the extreme lowering movement of the lower window sash as a whole. 65

A suitable stop member 84 is carried by the window frame 1 at the upper end of the way receiving the stile member 55, so that the stile member 55 of the lower window sash cannot be raised to the extreme upper end of the window frame. 70 The relative positions of the stile members 29 and 55 after the upper and lower sash frames have been opened, are clearly shown in Fig. 7. It will be observed that the lower edge of stile member 55 is below the lower edge of the stile member 29. 75

Operation

When it is desired to clean the outer faces of the window panes of the upper and lower sashes, the following manipulations are necessary, to-wit:

The lower sash is raised until the stile member 55 engages the stop member 84. When the lower sash has been thus raised, the operator withdraws the latch member from opening 73 of the stile member 55. The operator next lowers the hinged stop 82, as shown in Fig. 5 and then pulls down on the sash frame 22 until the stile member 53 engages the hinged stop 82. This pulling down movement of the lower sash frame 22 disconnects the lower sash frame from tongue and groove engagement with the stile member 55 so that just as soon as the lower sash is seated upon the hinged stop member 82 the lower sash frame 22 can be swung inwardly into a room so that the outside of the glass can be readily cleaned from within the room.

After the lower sash has been moved to its open position, the operator withdraws the latch member of the upper sash frame from engagement with the opening 45 of the stile member 29 and then pulls down on the upper sash frame 14. This pulling down movement of the upper sash frame is continued until the lower edge of the sash frame 14 and its hinged stile member 28 are just above the window sill, when then it is swung inwardly into the room so that the window pane can be cleaned from within the room.

To close the sashes again, the operator first swings the upper sash frame 14 to its closed position and then slides the sash frame 14 and its hinged stile 28 upwardly causing the tongue and groove connections of the sash frame 14 and stile member 29 to be connected. The latch on the upper sash frame is then moved into the opening 45 of the stile member 29 and the upper sash is then normally closed, so that the upper sash frame 14 and the stile member 29 can be lowered and raised together.

After the upper sash has been closed, the operator swings the lower sash frame 22 outwardly to its closed position, and then slides the sash frame 22 and its hinged stile member 53 upwardly causing the tongue and groove connections of the lower sash frame and the stile member 55 to be connected. The latch member of the lower sash frame is then moved into engagement with the opening 73 in the stile member 55 and the lower sash frame is then normally closed, so that the lower sash frame 22 and the stile member 55 can be lowered together.

From the foregoing description, it is evident that I provide a window structure, wherein the sashes can be raised and lowered in the usual manner and that they can be further opened inwardly into a room, so that the window panes thereof can be cleaned from within the room.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope 75 of the appended claims.

What I claim is:

1. In a window construction, a window frame, a window sash having a hinged stile weather strip connected with the window frame, a separable stile at the free swinging side of the sash, said separable stile embodying an inner section having its outer face provided with a groove extending from the top thereof to within a short distance of the bottom, the short distance thereof being provided with a tongue extending from the bottom face of said section to the lower end of the groove, the lower end of the groove and the upper end of the tongue having registered inclined faces, the other section of the separable stile being weather strip connected with the window frame and provided with a correspondingly long tongue extending from the top thereof on its inner face to slidably fit in the long groove aforesaid, and also provided with a short groove extending upwardly from the lower end of said stile to the lower end of the long tongue thereon, and said tongue and groove having registered inclined faces at their inner ends so that when the said tongues and grooves on the separable stile are in a sliding fit the separable stiles can be wedged together when the sash is moved upwardly relative to its outer stile section to effect a tight joint between the two sections of the separable stile.

2. A window construction having, in combination, a casing, an upper and a lower window sash, sliding stiles located on one side of the casing and having sliding metal weather strip connections with opposite sides of a parting bead strip, said window sash being hingedly connected to said sliding stiles, upper and lower sliding sash stiles located on the opposite side of the casing, the upper of said sash stiles having a sliding metal weather strip connection with an outside stop strip, the lower of said sliding sash stiles having a sliding metal weather strip connection with a parting bead strip, a tongue on said mentioned sliding sash stiles extending from the upper edge thereof to a predetermined point above the lower edges thereof and each provided with a beveled lower face, the upper and lower sash each having a corresponding groove in and out of which said stile tongues slide, said sliding sash stiles each having a groove below the tongue thereon and extending from the lower end of the tongues to the lower ends of the stiles, and the said upper and lower sash each being provided with a corresponding tongue having a beveled upper end extending from the lower ends of the sash tongues to the lower ends of said sash, said tongue and groove connections first permitting the lower sash proper to be swung on its hinges to open position after the lower sliding sash stile has been raised to its uppermost position and the lower sash then lowered and then the upper sash proper swung to its open position on its hinges after it has been lowered to its lowermost position.

3. A window construction having, in combination, a window frame provided with ways for window sash to slide up and down, a pair of window sash, each having a hingedly connected stile slidable in the ways on one side of the window frame, weather strip connections between the outer sections of said two piece hingedly connected stiles and the window frame, a separable stile embodying an inner and an outer stile section on the free swinging side of each window sash, weather stripping connections between outer stile sections and the frame, the inner section 75

of each separable stile having a longitudinal groove formed in its outer face and extending from the top edges thereof to points near the lower edges of said stile sections, inclined faces at 5 the lower ends of said grooves, a tongue longitudinally formed on the outer face of each separable stile section extending from the lower edges thereof and terminating at their upper ends in inclined upper faces in alignment with the 10 inclined faces at the lower ends of the grooves on the inner sections of the separable stiles, sliding bolt fasteners carried by the lower ends of each of the inner sections of the separable stiles, longitudinal tongues formed on the inner faces of the outer sections of the separable stiles corresponding to and co-acting with the grooves, on 15 the inner sections of the separable stiles, said

outer sections of the separable stiles having longitudinal grooves at their lower ends corresponding to and co-acting with the tongues on the inner stile sections of the separable stiles, said outer stile sections having openings in the inner 5 faces thereof adapted to receive the sliding bolt fasteners on the inner stile sections of the separable stiles to lock the stile sections against sliding movement relative to each other, and weight cords connected with the upper ends 10 of all the outer stile sections to hold the sash in any selected position and permit the sash to be lowered relative to the outer sections of the separable stiles and then swung to open positions. 15

JOSEPH P. BARBAY.
